UNITED STATES PATENT OFFICE.

C. NIXON, OF LIMA, OHIO.

BALING-PRESS.

1,125,381.

Specification of Letters Patent.

Patented Jan. 19, 1915.

Application filed February 20, 1914. Serial No. 820,025.

To all whom it may concern:

Be it known that I, MOSES C. NIXON, a citizen of the United States, residing at Lima, in the county of Allen and State of Ohio, have invented new and useful Improvements in Baling-Presses, of which the following is a specification.

My invention relates to improvements in baling-presses, and particular to division-block droppers for such presses; the objects being to provide means by which block-droppers may be operated by the action of the power mechanism, and means for locking the block-dropper when in normal position; and consists, preferably, in the construction hereinafter described, which may be varied without departing from the spirit of my invention.

In the drawings, Figure 1 is a side elevational view of the central portion of a baling-press having my invention applied, all parts not necessary to a clear understanding being omitted, and Fig. 2 is a plan view of the same.

Referring to the drawings, 1 is a portion of the baling-case of a baling-press, and 2 is the feed-aperture. Rearwardly of the feed-aperture and on opposite sides of the baling-case are secured two brackets 3 which support pivotal shaft 4, and to the shaft is secured a block-dropper 5. This block-dropper consists of two side bars 6 which are secured at their lower ends to shaft 4. The upper ends of bars 6 are secured to the division-block support or holder 7. Two legs 8 are also secured to opposite sides of the holder and to bars 6 and, in normal position of the dropper, the lower ends of legs 8 rest upon the top of the baling-case. The division-block holder is a frame secured to bars 6 and legs 8 and having a bracket 9 on one side which extends upwardly when the dropper is in normal position. This bracket is provided with an inwardly extending projection which is adapted to engage the upper surface of the division-block which is carried by or supported on the frame or holder 7. On the opposite side of the frame 7 is secured a flat spring 10 and secured thereto is a dog 11, which dog, having at its upper extremity an inwardly extending projection which is also adapted to engage the upper surface of the division-block. The top and inner side of dog 11 is sloping so that when inserted the downward pressure of the division-block will

force it outwardly. At the forward end of frame 7 and on opposite sides thereof are secured two flat springs 12 which releasably support the division-block when the dropper is rocked forward into position to drop the block through the feed-aperture into the baling-chamber. The division-block is first inserted under bracket 9 and then pressed downward into place, the dog being forced outwardly until the upper surface of the block passes the projection of the dog when the dog is forced inwardly by its spring and engages the edge and upper surface of the division-block and in conjunction with springs 12 secure the said block to the support or holder 7 and permit the dropper and block to be rocked on the pivot brackets and carry the block to the feed-aperture in the well understood manner.

A sleeve or hub 13 is loosely mounted on the shaft 4 and extending therefrom is a projection or member 14 and in the outer edge of this projection is a notch or recess 15. Also extending from the hub 13 is a lever 16, and at the lower or free end of this lever is pivotally connected a rod 17, which rod is adapted to be connected with the power mechanism in a manner to cause the rod to reciprocate and thereby impart a rocking movement to the lever 16 and projection 14. The power mechanism is not shown in the drawings as any suitable operating mechanism may be used.

To one of the bars 6 is secured a bracket 18 which is provided with projections 19 and 20. These projections are provided with holes and slidably mounted therein is a bar, lug or member 21, which bar is provided with a shoulder 22, and on said bar is an expansion spring 23 which presses against said shoulder and finds resistance against projection 19. The object of the spring is to force the bar or member toward the projection or member 14. Also to bar 6 is pivotally secured a lever 24, as by pin 25, which lever is connected with bar 21 by a rod or link 26, and from the hub of this lever is a projection having a slot 27 therein, which slot in conjunction with pin 28 limits the movement of the lever.

Pivotally secured to one of the legs 8 is a bracket 29, as by pin 30, and extending from this bracket is a projection provided with a slot 31, which slot in connection with pin 32 limits the movement of the bracket. One arm of this bracket forms a hook or latch

33, and the other arm a lever and pawl 34. A bar 35 is slidably mounted in brackets 36 and 37 and when the dropper is in normal position the lever 24 will rest upon the forward end of this bar. To the bar 35 is secured a casting 38, which casting is provided with a catch 39, and a raised portion 40 which forms a notch 41. Projecting downward from this casting is a lug 42 and through this lug and the rib of bracket 37 are suitable holes with a rod or bolt 43 therein, and on the bolt is an expansion spring 44. The length of the bolt should be such as to properly limit the movement of bar 35 and casting 38. Suitably supported and connected with the bar 35, is a lever 45, to which force may be applied to move the bar rearward, which is returned to normal position by the action of the spring.

20 In the construction shown the latch 33, and the lever and pawl 34 are in one piece pivoted to the leg and when the dropper is placed in normal position the lever contacts with the raised portion 40 and draws the 25 latch beneath the catch 39, where it is held and automatically locks the dropper until bar 35 is moved rearward and the pawl drops into notch 41, the latch and catch separate and the dropper is released. This construction permits the latch and catch to pass 30 and lock with less friction than if the latch was rigidly secured to the leg. But it is obvious that the latch and pawl could be made separate and the former rigidly secured to the leg and the bevel of the contacting parts of the latch and catch would enable the weight of the dropper to force the catch rearward until they pass when the action of the spring 44 would return the 35 catch and automatically lock the dropper.

In operation, when it is desired to drop a block, force is applied to lever 45, or other device for the purpose, and bar 35 is moved rearward until pawl 34 drops into notch 41 40 where it is temporarily held and releases the locking device. This movement also releases lever 24 from bar 35 and the member 21 is held in check by the rocking projection or guide 14 until the notch 15 is carried in front of the plunger when the latter is forced into the notch or recess by the pressure of the spring 23, thus forming an operating connection between the power mechanism and the dropper. Then as the dropper 45 is rocked forward pawl 34 is lifted out of the notch 41, and bar 35 is returned to normal position by the action of the spring 44, and the dropper is rocked forward and carries the block to the feed-aperture. Then 50 as the dropper is returned to normal position the lever 24 contacts with bar 35 and the plunger 21 is withdrawn from the notch 15 and the dropper is disconnected from the power mechanism and is automatically locked, to prevent it from being prematurely 55

carried to the feed aperture, until it is desired to drop another block when the operation is repeated.

What I claim is:

1. A baling-press having a power mechanism and a block-dropper, a member operated by the power mechanism and having a recess therein, a lug connected with the block-dropper, means to positively force the lug into said recess thereby forming an operative connection between the power mechanism and the block-dropper, and means adapted to disconnect said operative connection as the dropper is returned to normal position. 70

2. A baling-press having a power mechanism and a block-dropper, a member with a recess therein and adapted to be rocked by the power mechanism, a lug carried by the block-dropper, means to positively force the lug into said recess, and means to withdraw the lug from the recess as the block-dropper is moved to normal position. 85

3. A baling-press having a power mechanism and a block-dropper, a member adapted to be rocked by the power mechanism, a member carried by the block-dropper, positive means to force and hold an operative connection between the two aforesaid members whereby the block-dropper may be operated, and means adapted to disconnect said operative connection as the block-dropper is returned to normal position. 90

4. A baling-press having a power mechanism and a block-dropper, a member with a recess therein and adapted to be rocked by the power mechanism, a lug carried by the block-dropper, a spring adapted to positively force the lug into said recess whereby an operative connection is formed between 100 the power mechanism and the block-dropper, and means to disconnect said operative connection as the block-dropper is returned to 105 normal position.

5. A baling-press having a power mechanism and a block-dropper, means to intermittently connect the power mechanism with the block-dropper whereby the latter may be operated by the former, a device for locking the block-dropper when in normal position, and means for releasing the locking device. 110

6. A baling-press having a power mechanism and a block-dropper, mechanism for connecting the power mechanism and the block-dropper, means for locking the block-dropper when in normal position, and means adapted to release the locking device as said intermittent connection is formed. 115

7. A baling-press having a power mechanism and a block-dropper, a rocking member actuated by the power mechanism, a member carried by the block-dropper and adapted to form an intermittent connection between the rocking member and the block- 120

125 30

dropper, a device for locking the block-dropper when in normal position, and means for releasing the locking device.

8. A baling-press having a power mechanism and a block-dropper, means adapted to form an intermittent operative connection between the power mechanism and the block-dropper, a device for locking the block-dropper when the latter is moved to normal position, and means for releasing the same.

9. A baling-press having a power mechanism and a block-dropper, a mechanism adapted to form an intermittent connection between the power mechanism and the block-

dropper, a device for locking the block-dropper when in normal position, and means adapted to release the locking device and permit an operative connection to form between the power mechanism and the block-dropper whereby the latter may be operated.

In witness whereof, I hereunto sign my name this 14th day of February, 1914.

MOSES C. NIXON.
